UNITED STATES PATENT OFFICE.

REGINALD A. FESSENDEN, OF BROOKLINE, MASSACHUSETTS.

APPARATUS FOR CONVERTING HEAT INTO WORK.

1,132,465.

Specification of Letters Patent.

Patented Mar. 16, 1915.

Application filed April 8, 1912. Serial No. 689,179.

To all whom it may concern:

Be it known that I, REGINALD A. FESSENDEN, a citizen of the United States, and a resident of Brookline, in the county of Norfolk and State of Massachusetts, have invented certain new and useful Improvements in Apparatus for Converting Heat into Work, of which the following is a specification.

10 While my invention obviously is capable of adaptation to various types of thermic motors, I shall describe the same in connection with an internal combustion engine.

The accompanying drawings illustrate an 15 internal combustion engine comprising in its construction one embodiment of my invention.

In the drawings—Figure 1 is a view of what I term an “engine element,” the portion of said figure on the right of the irregular line X being shown in longitudinal section and the portion on the left of said line appearing in elevation. In this figure the pistons are shown in the position which 25 they occupy at the end of the explosion stroke. Fig. 2 is a similar view of said engine element showing the pistons in the position occupied at the end of the compression stroke. Fig. 3 is a view of an internal 30 combustion engine having the two engine elements shown in Figs. 1 and 2 arranged end to end, that portion of the figure to the right of the irregular line Y being shown in section and the portion on the left of said line being shown in elevation. In this figure the side plates 35 are omitted for clearness. Figs. 4 and 5 are transverse sections taken on the lines 4—4 and 5—5, respectively, of Fig. 3. Fig. 6 is a side elevation 35 of the engine shown in Fig. 3 as it appears from a point ninety degrees away from the view point of Fig. 3, with the side plates 35 in position. Fig. 7 is a transverse section taken on the line 7—7 of Fig. 3. Fig. 8 is 45 a fragmentary longitudinal section on an enlarged scale showing a modification of the cylinder construction.

In the particular drawings selected for more fully disclosing the principle of my invention, 1 1' are cylinders provided with the circular flanges or cylinder supports R R' respectively, each flange being shown in the present instance as cast integral with its cylinder. The pistons 3 3' coöperate

with the cylinder 1 and the pistons 3'' 3''' 55 with the cylinder 1'. Each piston is in non-contact fit with the inside of the cylinder and in contact fit with the outside thereof,—in other words, the sliding surface of contact between the piston and cylinder, or 60 the piston-bearing surface, is on the outside of the cylinder. In the present case this is effected by providing each cylindrical cup-shaped piston body 3 3' 3'' 3''' having an external diameter slightly smaller than the 65 internal diameter of the cylinder with an inclosing cylindrical bearing-member or sleeve 2 2' 2'' 2''', the internal diameter of which is equal to the external diameter of the cylinder. This is the salient feature of 70 my invention. By means of it I am enabled to overcome a number of difficulties heretofore experienced in this art and to accomplish various new and useful results as hereinafter more fully set forth.

75 In the engine of the prior art, where the sliding surface of contact between the piston and cylinder, or the piston-bearing surface, is on the inside of the cylinder, piston-packing rings, which for various reasons are objectionable, are necessary, as is well known, to compensate for the expansion of the cylinder and the contraction of the piston caused by the pressure exerted on these elements by the working fluid. But, 80 by means of my external piston-bearing, the use of such rings is rendered unnecessary, for the pressure created inside the cylinder causes both the cylinder 1 and the piston-bearing member 2 to expand in the same direction and tighten the contact there-between, the friction between these two elements varying directly with the pressure in the cylinder, so that for very large expansions, even expansions to or below atmospheric pressure, there are only very small frictional losses, the pressure between the piston-bearing member and the cylinder, and therefore the friction there-between, 85 being lessened as the pressure of the working fluid is reduced. In short, the engine is self-tightening and automatically-compensating for cylinder expansion to prevent leakage. For this reason piston rings are not needed. By referring to Fig. 2 for 90 further explanation with reference to a concrete example, it will be noted that when, as therein shown, the pistons are at the end 95 100

of the compression stroke, and the working fluid is in its state of maximum compression, the leakage surface is largest; but at this instant the pressure and friction between the cylinder and the piston-bearing sleeve is also a maximum, for the area of the cylinder exposed to the action of the working fluid is now much greater than that of the piston-bearing sleeve so exposed, the latter surface being equal merely to the combined areas of the ports 5" (or 5'') so that the cylinder expands at a greater rate than the piston-bearing sleeve, and such expansion tightens the contact between the cylinder and sleeve instead of pressing these elements apart. By virtue of this construction, very high pressures, for example one thousand pounds per square inch, are possible and practicable on compression, although in general such high pressures are not necessary.

As the engine is of the long-stroke type, the exhaust gases are much cooler than in the internal combustion engine heretofore employed, and a very long stroke may be used, because as above explained, the friction between the inside of the piston-bearing sleeve 2 and the outside of the cylinder 1 varies directly with the pressure of the working fluid.

I shall now proceed with the detail description of the illustrative embodiment of my invention shown in the drawings.

The cylinders 1 1' are provided near their ends with a plurality of ports 5 5' and 5" 5''' respectively, herein shown as eight in number, although of course any other suitable number may be employed, and the ends of the piston-bearing sleeves 2 2''' are provided respectively with the supplemental exhaust ports 7 7', (Figs. 1, 2 and 3,) of much smaller area than their coöperating ports 5 5''''. The external surface of the cylinders 1 1' on which the piston-bearing sleeves rub in their travel, are provided with lubricating-oil grooves 9 9' respectively, the construction being such that as is obvious, the hot products of combustion cannot come into contact with said grooves or the lubricant which by any suitable means may be supplied thereto, and each cylinder is provided with a fuel inlet tube or duct K K', such ducts being shown in the present instance as bored transversely through the flanges R R' (Figs. 1, 2, 3 and 4).

A pair of engine elements such as shown in Figs. 1 and 2 preferably are employed suitably mounted for coöperation, and as shown in Figs. 3 and 6, they may be mounted end to end in the following manner: To the flanges or cylinder-supports R R' are secured as by the screws r r' or otherwise two oppositely-disposed parallel steel sheets 35, 35 (see Figs. 4, 5, 6 and 7) so that the cylinders 1 1' remain in fixed position and

the lower ends of said sheets or side-plates may be mounted on a suitable base (not shown) or otherwise supported. The two inner pistons 3' 3'' herein shown as cast integral, are pivotally attached by the pin 31 70 passing transversely through the center of the casting, to the connecting rods 33 33, which in turn are connected to the cranks 34" 34'' secured to the crank-shaft 34. The two outer pistons 3 3''' are connected to the 75 encircling support 30 by the rods 15, herein shown as four in number, which are screwed into or otherwise attached to the lugs 13 13', preferably formed integral with the outer ends of the piston-bearing sleeves 2 2'''', respectively, and screwed into or otherwise attached to said support 30, said rods freely passing through the holes 15' in the flanges R R'. (Figs. 3, 4, 5 and 7.) Connecting rods 32 32 are pivotally attached to the support 30 by the pins 30', the inner ends of which extend beyond the ends of the pin 31, so that the latter will clear said support, and are connected to the cranks 34' 34' secured to the crank-shaft 34 at an angle of 85 one hundred and eighty degrees from the cranks 34''.

The length of the stroke being governed by the throw of the cranks, the pins 30' at the end of a half revolution of the crank-shaft from the position shown in Figs. 3 and 6 will be as far below the pin 31 as in said figures they are shown above the same.

It will be noted that one pair of rods 32 is always moving up under tension when 100 the other pair 33 is moving down under compression, and that such tension and compression are necessarily equal, as they are due to the same explosion in the same cylinder. Consequently there is no unbalanced 105 up or down pressure on the bearing of 34'', and this bearing could be eliminated if it were not necessary or rather desirable to fix the position of the shaft 34 relatively to the engine, in some way, and where this 110 is not necessary, or is done in another way, the bearing may be omitted. There is a side thrust which may be eliminated by suitable construction, but this is not necessary as it is very slight, owing to the fact 115 that the rods 32, 33 are more than ten times longer than the crank throw, and the cranks are at right angles to the axis of the piston when the expansion is half over and the compression much fallen. 120 For this reason and because at this instant each piston element pair is equally supported by its cylinder pair, and because with an ordinary 30-50 H. P. engine, the side thrust only amounts to less than ten 125 pounds per square inch, no piston or other guides are necessary, the cylinders themselves taking up the side thrusts and being well lubricated. On account of the perfect balancing and the perfect scavenging here- 130

inafter described, this engine can run at very high speeds. Taking the standard figures for velocity found practical for scavenging gases, the limiting velocity is in the neighborhood of twelve thousand revolutions per minute, a very high speed and one which would not be used in practice as a rule.

It will now be seen that the side-plates 35 10 may be thin metal sheets, as there is no force tending to displace the cylinder elements longitudinally, except the friction exerted thereon by the piston-bearing sleeve, for each piston acts equally and oppositely upon 15 its coacting piston. The engine is thus truly (and not merely apparently) balanced for all speeds. This is not true when the opposite moving pistons are in separate explosion chambers, as in this latter case, if one fails 20 to explode, the full unbalancing forces come into play.

It will be noted that the rods 15 which connect the outer pistons to the encircling support 30 are always under tension and that 25 therefore they may be of relatively small diameter.

Casings or containers 4 4', herein shown as cylindrical, are suitably attached to the flanges R R' respectively and inclose the upper half of the cylinder 1 and the lower half 30 of the cylinder 1', together with the pistons 3 3''' which coöperate with said cylinders. These containers or compression cases may be of any suitable material and may have 35 any desired shape and each will be provided with an automatic air inlet valve (not shown) as is usual in an ordinary two-cycle engine, see for example, the patent to Hurd 718,933, dated January 20, 1903 and the patent 40 to Newcomb 1,008,188, dated November 7, 1911, in which compression cases having the function of said containers 4 4' are illustrated and described in detail. Spark-plugs 18 18', if employed, may be screwed into the 45 bottoms of the cup-shaped pistons 3 3''', so that their spark points will project into the interior of the cylinders or compression chambers 1 1' respectively (Figs. 3 and 4.) Each spark-plug is provided with a terminal 50 36 36'.

Means preferably are employed to thermally insulate the interior of the combustion chamber from the cylinders and pistons. In the present instance I employ for this purpose the steel liners 10 10' for the cylinders 1 1' respectively and the steel liners 11 11' 11'' 11''' for the pistons 3 3' 3'' 3''', such liners being slipped in or over the cylinder and pistons, and mica strips M M' for the 55 cylinders and m m' m'' m''' for the pistons, the mica strips being placed between the liners and the cylinders or pistons as the case may be. This construction is shown in detail in Figs. 1, 2, 4, 7 and 8, but in Fig. 3, 60 which drawn to one-half the scale of Figs. 1

and 2, in order to simplify the drawing, the liners are not shown and the reference characters M M' m m' m'' m''' may be considered to represent the heat-insulating means shown in detail in the other figures.

70

It will be understood of course that instead of mica, any other suitable material may be used, as for example asbestos, or asbestos and silicate of soda, or even a plain air space, the liners being separated from the 75 walls by washers or projections, and instead of the steel liners, liners of mica, or asbestos, or silicon, or carborundum or other suitable material may be employed, or porcelain or similar material with or without wires or 80 wire netting embedded in it. The exposed surface of the liners may be provided with a coating E (see Fig. 8) of any suitable material such as mica, asbestos, fused soap-stone, or Bauer-Barfied (carbo-oxid of iron) 85 or they may be tinmed or nickelized or otherwise treated.

The ports preferably are bushed with thermal insulators 6, which may be of the same character as those used to heat-insulate 90 the cylinders and pistons and the lips L L' L'' L''' of the piston-bearing sleeves may also be heat-insulated as shown.

In operation the interior liners of the combustion chamber maintain a high temperature, which may be even a dull red, but as the heat cannot pass to the cylinder or piston, these remain cool, and the heat is expended in doing work or passes away with the waste gases, which may if desired, 100 be used to reheat the air for an air motor, or other purposes.

On account of the good heat insulation and of the high temperature of the liners, it is not necessary, as with the Diesel engine to use high compressions, though they 105 are preferred. Even at pressures of one hundred pounds the fuel will ignite, on being injected into the cylinders and on coming into contact with the liners; in which 110 case, of course, the spark plugs 18, 18' need not be used.

The thermal insulation may be supplemented by water-cooling as shown in Fig. 8, in which W represents water circulating 115 through passageways cast in the cylinder wall.

The construction above described is capable of various uses and, without limiting myself thereto, I shall now describe several 120 possible modes of operation.

When employed as an internal combustion engine, gaseous liquid or solid fuel, or any combination of such fuels may be employed, as is now well understood ... this 125 art. By means of apparatus now well known and which constitutes no part of my invention, oil or other fuel may be introduced through the ducts K K' in such a way as not to be entirely formed into a 130

mixture with air before introduction, although a mixture of air and gas, or of oil and coal-dust, etc., may be so introduced. Apparatus suitable for this purpose has been described by Diesel, for example in Letters Patent 542,846, July 15, 1895; 608,845, August 9, 1898, and 890,620, June 16, 1908. Such fuel so injected into the combustion chamber is exploded by contact with the heated air produced by compression or by contact with the hot liners 10 10' or otherwise in any of the methods described by Diesel and others. Near the end of the explosion stroke, the supplemental exhaust port 7 begins to uncover one of the ports 5 and the pressure in the cylinder 1 begins to fall. The ports 5, 5' then are uncovered by the piston-bearing sleeves 2 2' and the burned gases exhaust through 20 said ports. However, during the compression stroke (Fig. 2) the container is filled with air and this air, at the end of the explosion stroke (Fig. 1) is compressed. Therefore just as soon as the sleeve 2 begins to uncover the ports 5, the compressed air in the container or compression chamber 4 enters the cylinder by way of said ports and clears it of the products of combustion which pass out through the ports 5'. At 30 the end of the explosion stroke in cylinder 1, an explosion takes place in cylinder 1', piston 3''' is forced downwardly and carries piston 3 with it and piston 3'' is forced upwardly and carries piston 3' with it, the 35 said pistons 3 and 3' thus moving toward one another on their compression strokes, while the cylinder 1' is scavenged or cleared of the burned gases by the air compressed in the container 4' in the manner above set 40 forth in connection with the scavenging of cylinder 1.

In lieu of operating the engine as a Diesel engine, a gaseous mixture may be drawn into the containers 4 4' on the compression 45 strokes of the pistons 3 3''' by way of the automatic inlet valve referred to above as provided for the admission of air to said containers, and compressed in said containers on the explosion stroke of said pistons 3 3'''. In such case any desired 50 amount of pre-compression may be obtained and the mixture so compressed will flow into the cylinders by way of the ports 5''' thereby displacing the products of 55 combustion which pass out through the ports 5' 5'' in the usual well known manner, as described, for example, in the patent to Newcomb aforesaid. This pre-compressed mixture is of course further compressed until 60 the end of the compression stroke when, by means of spark-plugs or by the heat of compression, or otherwise, it is ignited and explodes, causing the pistons between which it was compressed to make their explosion 65 stroke, at the end of which a new charge is

received and the cylinder scavenged as before. It will be understood of course that where a mixture is pre-compressed in the containers and introduced by way of ports 5 5''', the ducts K K' are not necessarily 70 employed for fuel induction, although they may be so employed for injecting a rich mixture in cases where a lean mixture is admitted by way of ports 5 5'''. It will also be understood that when the engine is 75 operated as a Diesel engine, instead of admitting pure air by way of the ports 5 5''' and injecting fuel by way of the ducts K K', a lean mixture may be admitted by way of said ports and a rich mixture injected. 80

The idle space in the cylinders, between the sleeve 2 and the piston body 3, is preferably so proportioned that on compression the pressure of the gases or air filling the idle space is the same approximately as that 85 in the main cylinder. In this case there is but little exchange of air or gas between the idle space and cylinder, especially with the injected fuel method of operating, and practically no waste of energy, the energy 90 of compression of the gases or air in the idle space being given back on expansion. By this construction means is afforded for preventing the combustion from occurring in contact with the sliding surface between the 95 piston and cylinder, or the surface of the cylinder on which the piston rubs in its travel.

It will be seen that the engine is of the two-cycle type, because, as above described, 100 the ports open at one end of the stroke, allowing the burnt gases to flow out and admitting the air or mixture, and then compressing the air or mixture during the first half of the stroke, exploding the mixture or 105 injected fuel, and expanding during the second half of the stroke when exhaust again occurs; although it may be used as a four-cycle engine, and obviously my improved construction embodying said bearing pistons and thermally insulated parts may be 110 used in the steam engine, the air compressor or the air motor.

It will be noted that there are two impulses or explosions per revolution, because 115 there are two two-cycle cylinders, and in a two-cycle engine there is one explosion per revolution, so that two two-cycle cylinders in opposite phase, as in the present case, produce two explosions per revolution. The 120 engine therefore is double-acting and is equivalent to the four cylinders of a four-cycle engine and is much simpler and more efficient.

Heretofore in heat engines the efficiency 125 of the engine has been limited by the fact that the efficiency primarily depends upon the range of temperature of the working fluid, and this range has been limited by the heat losses due to conduction, evapora- 130

- tion, condensation, etc., in the cylinder and its neighborhood, and also by the fact that with high temperatures the piston moved over, and in contact with, the walls of the cylinder or combustion chamber, thereby limiting the temperatures to those at which lubrication was possible, where solid pistons were used, and to those at which the evaporation and cooling were not too excessive, where liquid pistons were used.
- 10 By my invention great economy in the use of fuel is attained. The thermal efficiency of heat engines is measured by the difference between the upper and lower limits of the 15 temperature of the working fluid, divided by the absolute temperature of the upper limit. Obviously therefore the lower the temperature of the issuing working fluid, the higher the efficiency. In the ordinary internal combustion engine, the issuing gas is 20 very hot, *i. e.*, the lower limit is high, and the efficiency low. In the steam engine it cannot go below the temperature of freezing water. But in my engine, for the reasons 25 hereinbefore stated, the expansion can be carried out to very low pressures and temperatures, so that the issuing working fluid may be many degrees below zero. Since the engine exhausts into the air, there would be 30 a back pressure unless the air was at the same temperature as the issuing fluid, and for this reason the whole engine may be placed in a chill room at any desired low temperature. Even without this, in large 35 sizes of 1,000 H. P. and upward, the thermal efficiency may reach over 80% and the brake efficiency over 70%.
- By means of my invention I am enabled 40 to overcome the difficulty heretofore experienced of maintaining the piston packing rings tight and cool, and the preferred form of my engine is balanced for all speeds, needs no cooling by water or air-flanges (though such cooling may be used if desired, 45 and in very large sizes is preferable) has no valves, springs, water pumps, fans, magneto, spark-plugs, timers, gears, shift-levers, clutch, bedplate, carburetor, etc., though any or all of these may be used.
- 50 By the term "piston" as used herein is meant that element of an engine which moves back and forth inside the cylinder and thereby changes the amount of working fluid in said cylinder.
- 55 Having thus described in detail one illustrative embodiment of my invention without, however, limiting the same thereto, what I claim as new and desire to secure by Letters Patent is—
- 60 1. A thermic motor comprising in combination a cylinder, a piston-body having its external diameter smaller than the internal diameter of said cylinder, and a sleeve secured to said piston-body and having its internal diameter equal to the external diameter of said cylinder, said sleeve having its bearing surface on the outside of said cylinder.
- 65 2. A thermic motor comprising in combination a cylinder and a piston, said piston being in non-contact-fit with the interior of said cylinder and in contact-fit with the exterior thereof, said piston having its bearing surface on the outside of said cylinder.
- 70 3. A thermic motor comprising in combination a cylinder, a cup-shaped piston having its external diameter smaller than the internal diameter of said cylinder, and a sleeve secured to said piston and having its internal diameter equal to the external diameter of said cylinder, said sleeve being co-extensive with said piston, and having its bearing surface on the outside of said cylinder.
- 75 4. A thermic motor comprising in combination a cylinder and a piston, said piston being in non-contact fit with the interior of said cylinder and in contact fit with the exterior thereof, said piston having its bearing surface on the outside of said cylinder, and a lining of heat-insulating material for said cylinder.
- 80 5. A thermic motor comprising in combination a cylinder and a piston, said piston being in non-contact fit with the interior of said cylinder and in contact fit with the exterior thereof, said piston having its bearing surface on the outside of said cylinder, and a lining of heat-insulating material for said cylinder.
- 85 6. A thermic motor comprising in combination a cylinder and a piston, said cylinder being provided with ports, and said piston being in non-contact fit with the interior of said cylinder and in contact fit with the exterior thereof, said piston having its bearing surface on the outside of said cylinder, and a heat-insulating lining for each of said ports.
- 90 7. A thermic motor comprising in combination a cylinder and a piston, said piston being in non-contact fit with the interior of said cylinder and in contact fit with the exterior thereof, said piston having its bearing surface on the outside of said cylinder, whereby the hot products of combustion are prevented from coming in contact with the surface of the cylinder on which the piston rubs in its travel.
- 95 8. An internal combustion engine comprising in combination a pair of cylinders, means supporting the same in end to end relation, two pairs of oppositely arranged pistons, one pair for each cylinder, each piston having its bearing surface on the outside of its co-acting cylinder, means connecting the two outer pistons together, other means connecting the two inner pistons together, a crank-shaft, cranks connected to said crank-shaft at an angle of one hundred and eighty de- 100

- grees apart, means connecting the two outer pistons to one crank and other means connecting the two inner pistons to the other crank.
- 5 9. A thermic motor comprising in combination a cylinder, a piston-body having its external diameter smaller than the internal diameter of said cylinder, a sleeve secured to said piston-body and having its internal diameter equal to the external diameter of said cylinder, said sleeve having its bearing surface on the outside of said cylinder, and means for thermally insulating said cylinder and piston-body.
- 10 15. 10. A thermic motor comprising in combination a cylinder, a piston-body having its external diameter smaller than the internal diameter of said cylinder, and a sleeve secured to said piston-body, said sleeve having its bearing surface on the outside of said cylinder and other means connecting the two outer pistons to one crank and other means connecting the two inner pistons to the other crank.
- secured to said piston-body, said sleeve having its bearing surface on the outside of said cylinder.
11. A thermic motor comprising in combination a cylinder, a piston-body having its external diameter smaller than the internal diameter of said cylinder, a sleeve secured to said piston-body, said sleeve having its bearing surface on the outside of said cylinder, and means for thermally insulating said cylinder and piston-body.
- In testimony whereof, I have hereunto subscribed my name this 6th day of April 1912.
